UNITED STATES PATENT OFFICE.

JOHN E. GAMBLE, WILLIAM HARRISON, AND ALLEN R. LEE, OF EAST LIVERPOOL, OHIO; SAID LEE ASSIGNOR TO FLENTKE, HARRISON & CO., OF SAME PLACE.

DESIGN FOR A ROASTING AND BAKING DISH.

SPECIFICATION forming part of Design No. 13,496, dated December 26, 1862.

Application filed November 8, 1862. Term of patent 7 years.

To all whom it may concern:

Be it known that we, JOHN E. GAMBLE, WILLIAM HARRISON, and ALLEN R. LEE, citizens of the United States, residing at East Liverpool, in the county of Columbiana and State of Ohio, have invented and produced a new and original Design for a Roasting and Baking Dish, of which the following is a specification, reference being had to the accompanying drawing, forming part thereof.

The figure is a perspective view of our newly-designed roasting and baking dish.

A represents the body of our roasting and baking dish, provided with the vertical scallops aa and handles BB. Around the upper edge of the dish is an ornamental cornice or band, C, within which fits the cover D, and the bottom has a projecting edge, E. The cover D rises gradually in scalloped sections dd and is surmounted with a handle, F, all as shown in the accompanying drawing.

We claim—

The design for a roasting and baking dish herein shown and described, the same consisting of the dish A, provided with the vertical scallops aa, handles BB, and ornamental cornice or band C, and the cover D, consisting of the scallops dd and handle F.
